UNITED STATES PATENT OFFICE.

ALFRED HEALD, OF PHILADELPHIA, PENNSYLVANIA.

WOVEN FABRIC.

SPECIFICATION forming part of Letters Patent No. 605,783, dated June 14, 1898.

Application filed April 5, 1897. Serial No. 630,786. (Specimens.)

To all whom it may concern:

Be it known that I, ALFRED HEALD, a citizen of the United States, residing in Philadelphia, Pennsylvania, have invented certain 5 Improvements in Woven Fabrics, of which the following is a specification.

My invention consists of certain improvements in the woven fabric for which I obtained Letters Patent of the United States, 10 No. 198,615, dated December 25, 1877, one object of my present invention being to produce a fabric having the combined ingrain and damask effects upon the surface, as in said patented fabric, without the use of any 15 heavy damask weft-threads embedded in the body of the fabric, a further object being to provide for greater variety of coloring in the pattern of the fabric, and a still further object being to economize in the use of the damask 20 warp-thread.

In the accompanying drawings, Figure 1 is a face view of a piece of fabric embodying my present invention without any attempt being made to represent the weave. Fig. 2 25 is an exaggerated section of the fabric, taken in the direction of the warp. Fig. 3 is a like exaggerated section of the fabric, taken in the direction of the weft; and Figs. 4 and 5 are sections similar to Fig. 2, but illustrating 30 special forms of the fabric.

In the fabric forming the subject of my before-mentioned patent I combined ingrain and damask plies, which were transposed according as either was required to appear upon 35 the face of the fabric, the other ply going to the back. The ingrain ply was composed of interwoven fine warps and heavier wefts, and the damask ply was composed of face-warps, heavy filling threads or wefts, and alternate 40 fine wefts with which one or other of the warps of the ingrain ply engaged, so as to confine the two plies of the fabric firmly together. Viewed in one light, therefore, the ingrain ply of my patented fabric took the place of one of the 45 face-warps of a true damask fabric, while viewed in another light the damask ply took the place of the second ply of a true two-ply ingrain fabric. The heavy weft-thread of the damask ply was used, as in a true damask 50 fabric, simply as a stuffer-thread to give body to the fabric and to provide for the deep drawing down or indenting of the warp-

threads between the filling or stuffer threads, which is characteristic of such damask-carpet fabric. In my present fabric I produce 55 the damask effect due to the deeply-indented warps without the use of the stuffer-wefts, and I form the ingrain ply by combining fine binding-warps with sets of weft-threads in such manner that either thread of the set 60 may appear upon the face of the fabric, where its appearance is necessary for the production of the proper pattern. All of the ingrain weft-threads of a set are by preference introduced into the same shed of the warp and 65 when at the back of the fabric lie in the same horizontal plane. These features, however, are not absolutely essential to the broader embodiment of my invention.

In Figs. 2 and 3 of the drawings, A A represent the damask warp-threads, which may, for instance, be dark blue, and B and Y the ingrain weft-threads, which may be light blue and yellow, respectively, a a' representing the ingrain warps, and b the damask tying-weft. 70

In the section of the fabric marked x the damask warp is on the face and the ingrain ply at the back, while in the section of fabric marked w the weft-threads B are on the face, the weft-threads Y at the back, and the damask warps A between them, and in the section of fabric marked y the weft-threads Y are on the face, the weft-threads B at the back, and the damask warps A between them. Hence it 75 will be seen that each of the main threads of 80 the fabric is available for use individually in any part of the pattern, so that patterns of a more elaborate character and of wider range of coloring are possible than with the patented fabric. 85

The damask warp is embedded between the face and back wefts instead of being carried to the back of the fabric, partly in order to separate said wefts and prevent them from appearing side by side on the face of the 90 fabric and partly for purposes of economy, considerably less damask warp being required when this disposition of the same is resorted to than when said damask warp is carried to the back of the fabric. 95

There is, as before remarked, in my improved fabric no stuffer-thread over which the damask warp is drawn so as to produce 100 the deeply-indented effect characteristic of

the true damask fabric, and in order to produce substantially the same effect I subject the fine binding-warps *a a'* of the ingrain fabric to such a tension as will draw down 5 tightly the fine binding-wefts *b*, and thereby deeply indent or compress the comparatively soft damask warps *A* wherever they are bound by said wefts *b*.

In Fig. 4 I have shown a fabric in which the 10 ingrain wefts are in sets of three, lettered, respectively, *B*, *Y*, and *R*—say, for instance, blue, yellow, and red—two threads of the set remaining at the back of the fabric whenever the third thread is carried to the face, and in 15 Fig. 5 I have shown a fabric similar in structure to that represented in Fig. 2, but with threads of different color in successive sets. Thus one set is composed, say, of a green thread *G* and a mixed thread *M*, while the next set 20 is composed of a green thread *G* and a red thread *R*, a thread of like color being used in both sets in order that the fabric may be woven with the ordinary four-box ingrain loom, three of the boxes carrying the shuttles 25 for the threads *G*, *M*, and *R* and the fourth carrying the shuttle for the fine binder-weft *b*.

The term "damask warp-thread" as herein used is intended to mean a warp-thread which when it appears upon the face of the fabric 30 is compressed and deeply indented at regular intervals by a fine binding-weft, and said warp-thread may consist of a single strand or of any desired number of strands controlled as a unit by the shedding mechanism 35 of the loom.

In weaving my improved fabric the warps *a a'* are controlled by the heddle frames or journals of the loom, as usual, or by a jac- 40 quard machine constructed to shed these warps in the same manner as such heddle frames or journals, the warps *A* being under control of a jacquard machine, so as to be raised and lowered in accordance with the exigencies of the pattern when the ingrain 45 wefts are being inserted, and said machine being also capable of operation so as to shed the warps *A* in the same manner as journals or heddles for the insertion of the fine wefts *b*. The ingrain wefts of each set are intro- 50 duced successively, and in inserting each set of these wefts each warp *A* is raised during the insertion of the entire set where said warp is to appear upon the face of the fabric, but is lowered for one pick and raised for the re- 55 maining pick or picks of the set where it is to pass between the face and back wefts of the fabric, or it may be lowered during the insertion of the entire set if it is desired to carry it to the back of the fabric.

Having thus described my invention, I claim and desire to secure by Letters Patent—

1. A woven fabric in which damask warps, ingrain wefts, fine binding-warps, and a fine damask binding-weft are combined so as to 60 form the face of the fabric in part of damask warps compressed and deeply indented by the fine binding-weft, and in part of ingrain wefts

bound by the fine warps, substantially as specified.

2. A woven fabric in which damask warps, 70 ingrain wefts in sets, fine binding-warps and a fine damask binding-weft are combined so as to form the face of the fabric in part of damask warps compressed and deeply indented by the fine binding-weft and in part 75 of ingrain wefts independently displayed and bound by the fine warps, substantially as specified.

3. A woven fabric in which damask warps, 80 ingrain wefts in sets, ingrain binding-warps, and a fine damask binding-weft, are combined as described whereby the face of the fabric is composed in part of damask warps, compressed and deeply indented by the fine binding-weft, and in part of ingrain wefts independently displayed and bound by the fine warps, the ingrain wefts of each set lying 85 side by side in the same horizontal plane on the back of the fabric where the damask warps appear upon the face, substantially as 90 specified.

4. A woven fabric in which damask warps, ingrain wefts in sets, ingrain binding-warps, and a fine damask binding-weft, are combined as described whereby the face of the 95 fabric is composed in part of damask warps compressed and deeply indented by said fine binding-weft, and in part of ingrain wefts independently displayed and bound by the fine warps, the ingrain wefts of each set being inserted in the same shed of binding-warp and said ingrain wefts lying side by side in the same plane on the back of the fabric where the damask warps appear upon the face, substantially as 100 specified.

5. A woven fabric comprising damask warps, ingrain wefts in sets, ingrain binding-warps, and a fine damask binding-weft, the face of the fabric being composed in part of damask warps compressed and deeply indented by the fine binding-weft, and in part 110 of ingrain wefts independently displayed and bound by the fine warps, the damask warps lying between ingrain wefts upon the face of the fabric and ingrain wefts upon the back 115 of the fabric wherever such damask warps do not appear upon the face, substantially as specified.

6. A woven fabric comprising damask warps, ingrain wefts in sets, ingrain binding-warps and a fine damask binding-weft, the face of the fabric being composed in part of 120 damask warps compressed and deeply indented by the fine binding-weft, and in part of ingrain wefts independently displayed and bound by the fine warps, said ingrain wefts lying side by side in the same plane at the back of the fabric where the damask warps appear upon the face, and said damask warps lying between ingrain wefts on the face of the fabric and ingrain wefts upon the back 125 of the same, wherever they do not appear upon the face, substantially as specified.

7. A woven fabric comprising damask

warps, ingrain wefts comprising repetitions of two pairs with a like thread in each pair, ingrain binding-warps and a fine binding-weft combined as described whereby the face 5 of the fabric is composed in part of damask warps compressed and deeply indented by the fine weft, and in part of the ingrain wefts independently displayed, said wefts lying side by side at the back of the fabric when 10 the damask warps are on the face, and said damask warps lying between ingrain wefts of

the face and back of the fabric wherever they do not appear upon the face, substantially as specified.

In testimony whereof I have signed my 15 name to this specification in the presence of two subscribing witnesses.

ALFRED HEALD.
